Application June 23, 1949, Serial No. 3,464

Term of patent 14 years

(Cl. D74—1)

To all whom it may concern:

Be it known that we, Donald E. Beckett, William N. Beckett, Robert E. Wasmuth and Homer Kenneth Ware, citizens of the United States, the Becketts each residing at Wilmington, in the county of Clinton, and State of Ohio; Wasmuth and Ware residing at Huntington, in the county of Huntington and State of Indiana, have invented a new, original, and ornamental Design for a Combination Nailer and Stapler, of which the following is a specification, reference being had to the accompanying drawing, forming part hereof.

Fig. 1 is a side view of the combination nailer and stapler showing our new design, it being understood that the opposite side is a substantial duplicate of the side illustrated.

Fig. 2 is a top view of the device of Fig. 1.

Fig. 3 is a rear view of Fig. 1.

Fig. 4 is a front view of the device.

We claim:

The ornamental design for a combination nailer and staple, as shown and described.

DONALD E. BECKETT.
WILLIAM N. BECKETT.
ROBERT E. WASMUTH.
HOMER KENNETH WARE.
